UNITED STATES PATENT OFFICE.

HARRY BARRINGER COX, OF LOS OLIVOS, CALIFORNIA.

METHOD OF RIVETING AND APPARATUS THEREFOR.

1,365,664.

Specification of Letters Patent. Patented Jan. 18, 1921.

Application filed October 8, 1917. Serial No. 195,303.

To all whom it may concern:

Be it known that I, HARRY BARRINGER Cox, a citizen of the United States, residing at Los Olivos, in the county of Santa Barbara, State of California, have invented a new and useful Method of Riveting and Apparatus Therefor, of which the following is a specification.

Heretofore hot rivets have had their ends set or shaped by hammering, either by hand or by pneumatic or electric riveting devices which give a hammering effect.

The object of this device is to substitute rapid rotation of the riveting tool as a mechanical equivalent to hammering, and by the use of a properly formed shaper tool, to spin the semi-plastic hot rivet so that it may be headed or what is commercially termed "set".

Three forms of the device are shown. One in which the shaft to which the shaper tool is attached is rotated at a high speed by an electric motor. One in which compressed air is made to operate a rotary pneumatic engine which rotates the shaft to which the shaper tool is attached. Another is shown in which the shaft is rotated by an electric motor which automatically supplies the pressure needed by the sucking in of the armature into the magnetic field of the pole pieces.

In this last device, the apparatus is held by magnetism against the plate through which the hot rivet is inserted. While this last mentioned device shows how the comparatively slight pressure needed is applied, in the other two devices first named, the pressure is applied by pushing the tool against the plastic hot rivet.

This device has many advantages over any heretofore used or which are now in use, for instance, the operation is much quicker performed by spinning than by hammering as the high speed of rotation is the mechanical equivalent of the comparative slow movement of any to and fro device, such as the present mechanical riveter in ordinary use.

It also has the advantage of saving the operator from the severe physical effort and shock to which he is subjected by all existing rivet setting devices.

It also is much more economical in its operation as much less energy, either pneu-

matic or electric, is required to produce rotation than to produce the to and fro hammering effect.

Under the existing conditions of the world's needs for speed in marine construction, the device can readily be seen to lend itself most admirably, as it does not require the construction of additional power plants, either pneumatic or electric, but will necessitate only the use of this easily constructed and economically operated device by the existing plants.

In the drawing showing the shaper tool, as I term the heading device, I show one form in which the cup shaped tool has a transverse ridge extending down one side across the bottom and up the other side. The object of this ridge is to produce a squashing effect on the semi-plastic rivet so that it may more readily take on the form to be desired.

It will be understood, however, that when the head of the rivet is finished, it will be not of the size of the cup but will conform to the size of the raised projection.

My present invention in its broad and generic scope comprehends the setting of a hot semi-plastic rivet by a rapidly rotated spinning shaper, and I do not desire to limit myself either to the form of power employed to cause the shaper tool to spin, or to the definite shape of the shaper tool.

In one form of my novel device, I employ a casing containing a rotary armature, pole pieces and field magnets and utilize a spinning or rotary motion of the rivet set to form the rivet head, the armature when being drawn into the pole pieces giving the needed pressure to form the rivet head. In the operation of this embodiment of my device, when the hot rivet is in position, the open pole pieces are brought into contact with the iron plates through which the rivet extends, and when said pole pieces are properly energized by the electric current flowing through them, they will cling tightly to the contacting iron plate closing the magnetic circuit and so completing the polarity of the field poles, causing the armature to rotate at a high speed and at the same time to be drawn or sucked into the pole pieces.

This combined spinning and rotary action of the rivet set at one and the same time

forms the rivet head, since a very great pressure is exerted when the armature is drawn into the field poles.

My invention is of particular commercial benefit since it reduces the time of heading a rivet to a fraction of the time now necessary, even in the best of the commercial devices, and it also has the particular advantage of lightness of weight for the operator to handle, and an additional very important advantage is that the shock and nerve strain that the operator is under with the present type of pneumatic riveter is entirely done away with in my device, there being no strain whatever, as the device clamps against the iron plate and is held in that position free from all strain on the part of the operator and remains in that position until the entire riveting operation has been finished. It is then readily detached by merely opening the electric circuit by a manually operated switch which can be operated by a thumb or finger of the workman from the grasping handle of the tool, which latter will be light in weight and easily and cheaply constructed, and readily portable.

To the above ends, my invention consists of a novel method of riveting and apparatus therefor, wherein a rotary movement, and if desired an axial movement, is imparted to a working tool, such as for example, a rivet set.

In a divisional application Serial No. 225,175, filed March 28th, 1918, I have shown and described the modification shown in Fig. 4.

Other novel features of construction and advantage will hereinafter more clearly appear in the detailed description of my invention.

For the purpose of illustrating my invention, I have shown in the accompanying drawings typical embodiments of it which are at present preferred by me, since these embodiments will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a magnetic riveter, embodying my invention.

Fig. 2 represents a longitudinal, sectional view of Fig. 1, showing also in section a pair of plates and a rivet therethrough to which my invention is applicable.

Fig. 3 represents in section the armature shaft and a detachable working tool.

Fig. 4 represents a longitudinal, sectional view, partly in elevation, of another embodiment of my invention.

Fig. 5 represents a view similar to Fig. 4 of another embodiment of my invention.

Fig. 6 represents an end view of a rivet set embodying my invention.

Fig. 7 represents a side elevation, partly in section, of the rivet set seen in Fig. 6, showing the roughened or ridged formation on the concaved face of the rivet set.

Similar numerals of reference indicate corresponding parts.

Referring to the drawings:—

1 designates my novel construction of pneumatic riveter, the same comprising an outer casing 2, preferably of insulating material or properly insulated, which may be of any suitable contour or configuration and provided with a handle 3 for holding the tool up to its work.

The casing 2 may inclose the device at its rear end, as indicated at 4, the forward or left hand end thereof being closed by a suitable closure, such as a disk, plate or the like, 5.

Within the casing 2, I locate the lining member 6, which has an inwardly extending bearing 7 for the end 8 of the rotatable shaft 9, which carries the armature 10, the forward end of said shaft having its bearing in the guide bar or plate 11.

12 designates a rivet set which is preferably detachably connected to the rotatable shaft 9, see Fig. 3, the same being adapted to contact with and drive or head the end 13 of the rivet 14, which is shown in Fig. 2 as passed through the contiguous plates 15 and 16.

17 designates an adjustable stop or abutment carried by the rotary armature shaft 9 for the purpose of limiting the forward movement thereof. Within the casing 2 are located field magnets 18 through which pass the pole pieces 19 and 20, said pole pieces terminating in the enlarged ends 21 which are provided with recessed portions 22 so as to permit a longitudinal forward movement of the armature 10, the shaft 9 and its adjuncts to the desired extent, as will be hereinafter explained.

23 designates a commutator and 24 the commutator brushes. The handle 3 is preferably forged or similarly constructed and may be attached to the body or casing 2 by means of rivets 24 or other suitable fastening devices or it may be spotwelded thereto, as at 25, as is evident.

The guide bar 11 through which the armature shaft 9 passes and in which it is rotatably mounted may be secured in fixed position with the pole pieces 20 by means of set screws 26 or other fastening devices.

The handle 3 is preferably made hollow, as indicated in Fig. 2, whereby the chamber 27 is provided, as indicated in Fig. 2 in which I locate the circuit closing and opening devices 28 and 29, the upper circuit closing de-

vice or spring 28 being actuated by the depression or finger piece 30, whereupon the circuit is closed, the magnets 18 energized and the rotation of the armature 10 and 5 shaft 9 effected by any suitable wiring system, as will be familiar to those skilled in the art.

The handle chamber 27 forms a receptacle for the electric conductors indicated at 31 10 and 32 and it will be apparent that when the outer terminals of the pole pieces 19 and 20 are placed against the plate 16, the circuit will be closed and the lines of force travel in the direction indicated by the arrows 33 15 so that the armature 10, shaft 9 and button set 12 not only acquire a rapid rotatable movement, but in addition, owing to the magnetism created in the pole pieces 21, said armature will be drawn axially to the left, 20 thereby imparting not only a spinning but a pressing action to the red hot end 13 of the rivet 14 so that the latter will be headed in a period of a few seconds.

The working tool is preferably made detachable and one manner of accomplishing this result is indicated in Fig. 3. The armature shaft 9 is provided with a head or socket 33 having an aperture 34 adapted to receive the shank of the rivet set or other working 30 tool 12, which may be removed by actuating the drift pin 35. This pin 35 engages the walls of the recesses 36 and 37 in the socket 33 and shank of the working tool, respectively, so that such parts revolve together.

35 When the circuit is closed through the pole pieces and the plates which are to be riveted, the magnetic force created securely holds the riveter with respect to such plates until the circuit is broken. This renders it 40 much easier for the operator to handle the riveter, since all that it is necessary for him to do is to place it in proper position with respect to the work and then close the circuit, whereupon the rivet will be properly 45 headed. As soon as this operation is completed, the operator opens the circuit, thereby releasing the riveter from its work and it is ready to be applied to the next rivet which is to be driven.

50 Referring now to the embodiment seen in Fig. 4, an electric motor driven riveter is illustrated in which a rotary motion is imparted to the rivet set to cause the setting of a rivet head through the medium of its 55 rotary or spinning action.

38 designates a sectional casing, each section of which is provided with ears 39 secured together by fastening bolts 40. To the rear portion of the casing 38 a handle 41 60 is secured for holding the tool to its work.

The casing 38 may have any desired contour and as shown is cylindrical in longitudinal section and is provided with end closure walls 42 and 43 which provide a bearing for 65 a rotatable shaft 44 carrying an armature

45 of an electric motor 46 inclosed in the casing 38.

47 designates a rivet set which is preferably detachably connected to the rotatable shaft 44 in a manner similar to that shown 70 and described with reference to Fig. 3.

48 designates a grasping handle loosely mounted on the rotatable shaft 44 intermediate the casing 38 and the head or socket 33 of the rotatable shaft 44 and is held 75 against longitudinal movement on said shaft 44 between the collar 49 fixed to the shaft and the hub extension 50 of the casing 38.

The function of this handle is to afford a 80 grasping portion for the hand of the operator to support and direct the front end of the tool in the one hand independent of the rotary movement of the shaft 44, while the main support of the tool is maintained by grasping the handle 41 with the other hand. 85

The design of the handle 41 and its manner of attachment to the casing 38 is similar to that shown in Figs. 1 and 2 of the drawings and heretofore described.

The motor 50 is of the ordinary type consisting mainly of the coiled field pieces 51 fixed to the casing 38. Between these field pieces 51, the armature 45 is mounted to rotate with its rotatable shaft 44 bearing in the end walls of the casing and carrying the rivet set 47. The armature is provided with a commutator and stationary insulated brushes in the same manner as shown in Fig. 2 of the drawings.

The arrangement of the electric wiring of 100 the motor together with the mechanism for starting and stopping the motor is similar to that shown in Fig. 2 of the drawings and heretofore described.

In the embodiment of riveter, seen in Fig. 105 5, compressed air or other motive fluid is utilized as the energy to operate the device, the general operation and construction being substantially the same as that shown in Fig. 4, except that a rotary engine 52 is 110 mounted within the casing to actuate the rotatable shaft 44. This rotary engine may be of any desired or conventional type and for purposes of simplicity, I have shown a plurality of blades 53 carried by the shaft 41 115 to rotate said shaft when motive fluid is admitted into the casing 38 to act against said blades.

54 designates a port in the end wall 43 of the casing 38, said port 54 being in communication with the interior of the casing 38 and with a passageway 55 in the handle 56. 57 designates a flexible tube in communication with a supply of motive fluid and with a passageway 58 in the handle 56. 59 designates a manually actuated valve operated by the finger trigger 60 for controlling the passage of motive fluid from the passageway 58 into the passageway 55, thence through the port 54 to operate the rotary en- 130

gine 52 carried on the rotary shaft 44. The casing 38 is provided with an exhaust port 66 for the exhaust of motive fluid from the casing.

5 Referring to Figs. 6 and 7 of the drawings, a modified embodiment of rivet set or shaper tool is shown more particularly adapted for use in connection with riveters, such as shown in Figs. 1, 2, 4 and 5 of the 10 drawings and heretofore described, in which a rotary or spinning action of the rivet set is relied on to set or spin the rivet head into shape.

When a rotary or spinning motion is employed, it is sometimes desirable that the 15 surface of the concaved portion of the rivet set be roughened or ridged to aid in the spinning of the rivet so that its head will receive the desired set in the least time and 20 eliminate the physical strains to which the operator is subjected in the operation of riveters of the hammering type.

With this end in view, I have shown a 25 rivet set or shaper tool 61 consisting of the headed portion 62 provided with an integral shank 63, the headed portion 62 being concaved, as shown at 64. One form of configuration to produce the above desired results consists in forming a transverse ridge 30 65 on the curved surface of the concaved portion 64.

Various other forms of configuration on 35 this curved surface may be resorted to to produce the desired results. It will readily be understood that with a rapidly rotating shaper tool of this character the ridge 65 will have a combined squashing and spinning action on a semi-plastic rivet to quickly form the rivet to the desired shape or set.

40 It will be apparent that all of the working parts are properly protected or concealed within the casing, so that the riveter is fool proof and there is no chance for any one to become injured by coming in contact with 45 the working parts or the parts of the electric circuit.

While I have described my invention as being especially adapted to be employed 50 as a riveter, it will be apparent to those skilled in the art to which this invention appertains that it is adapted to be employed in all cases in which a simultaneous rotary and axial movement of a working tool is desired.

55 It will be seen that owing to the provision of the pole pieces and the manner in which the current is formed through the work, such as for example, the plates which are to be riveted, reamed, drilled, or otherwise 60 acted upon, I provide a magnetic holder-on which securely clamps the apparatus with respect to the work when the electric circuit is closed and when the electric circuit is open, the device is automatically detached from the work. By such construc-

tion, the different operations which are capable of being performed by a rotation and forward feed of the working tool can be very expeditiously performed, and since the operator does not have to rigidly hold the tool, the work can be accomplished with a minimum amount of labor on the part of the operator, as is evident.

It will be apparent from the foregoing that in the broad and generic scope of my invention, I provide means for spinning into shape the end or head of any desired member, such as for example, a rivet set, and while in some cases, it is desirable to secure the riveter with respect to the work, in other cases, it is manually supported and can be manually manipulated so that the spinning element can be adjusted with respect to the work which is being accomplished.

It will now be apparent that I have devised a novel and useful method of riveting and apparatus therefor, which embodies the features of advantage enumerated as desirable in the statement of the invention and the above description, and while I have, in the present instance, shown and described typical embodiments of it which will give in practice satisfactory and reliable results, it is to be understood that these embodiments are susceptible of modification in various particulars without departing from the spirit or scope of the invention or sacrificing any of its advantages.

Having thus described my invention, what I claim as new and desire to secure by Letters Patent, is:—

1. In an electric riveter, the combination with a rivet set, of electrically actuated means to simultaneously rotate said rivet set and advance it to its work.

2. In an electric riveter, the combination with a rivet set, of electrically actuated means to simultaneously rotate said rivet set and advance it to its work, and manually controlled devices to render said means operative or inoperative.

3. In an electric riveter, a casing, an armature rotatably mounted in said casing, a magnetic field for said armature including pole pieces extending exterior of the casing, means to energize and deenergize said magnetic field, said magnetic field when energized effecting a rotation and an axial movement of said armature, and a working tool carried by said armature.

4. A device of the character stated, comprising a casing, an armature therein mounted for rotary and axial movement, a magnetic field for said armature, means to energize and deenergize said magnetic field, a working tool rotated and moved axially by said armature, a magnetic holder-on, and electrical means to control said magnetic field and said magnetic holder-on.

5. A device of the character described, comprising in combination, a casing, an electric circuit including a magnetic field, a rotatable and axially movable armature and pole pieces within said casing, said pole pieces extending exterior of said casing to form a magnetic holder-on when the circuit is energized, a working tool actuated by said armature, and manually actuated means to control the opening and closing of said circuit. 10
6. A device of the character described, comprising in combination, an electric motor adapted to simultaneously rotate and axially move, an electric circuit for said motor, a rivet set connected to said motor, pole pieces carried by said motor to engage the work and form a circuit therethrough when said electric circuit is energized, and means 15 to control said electric circuit. 20
7. A device of the character described, comprising in combination, a casing, a support within said casing, an armature journaled in said support, pole pieces within said casing extending exterior thereof, a magnetic field for said pole pieces, a shaft for said armature extending exterior of said casing, a guide for said shaft carried by said pole pieces, a stop for said shaft, a 25
- working tool carried by said shaft, and means to pass electric current to said armature and to said magnetic field. 30
8. A device of the character described comprising in combination, a casing of insulating material, an electric motor within said casing, a working tool carried by said motor, an electric circuit for said motor to cause it to simultaneously rotate and move longitudinally, means to control said circuit, a working tool carried by said motor, 35 and means controlled by said circuit to clamp said casing with respect to the work to be performed. 40
9. A device of the character described, comprising in combination, a casing, a support within said casing, brushes carried by said support, an armature rotatable in said casing and support, pole pieces extending exterior of said casing and partially surrounding said armature, an armature shaft, 45 a working tool detachably connected with said shaft, and means to energize or de-energize said magnetic field and pass an electric current to and from said brushes. 50
